UNITED STATES PATENT OFFICE.

JOHN BUTMAN, OF MILAN, OHIO.

POTATO-DIGGER.

SPECIFICATION forming part of Letters Patent No. 355,637, dated January 4, 1887.

Application filed September 25, 1886. Serial No. 214,490. (No model.)

To all whom it may concern:

Be it known that I, JOHN BUTMAN, of Milan, in the county of Erie and State of Ohio, have invented a certain new and Improved Potato-Digger; and I do hereby declare that the following is a full, clear, and complete description thereof.

The nature of my invention relates to the mechanism employed for removing the potato toes from the hills or rows and sifting them from the earth.

It also relates to the means for disconnecting said mechanism from the primary operating parts when the machine is turning about, backing, or traversing when not in use.

To enable others to fully comprehend the construction and mode of operation of the said potato-digger, attention is directed to the following specification, and to the annexed drawings, in which like letters denote like parts.

Figure 1 is a vertical section in direction of the line $\alpha\alpha$ in Fig. 2. Fig. 2 is a plan view, and Fig. 3 is a detached section, as represented in the annexed drawings, and in which—

A A are carrying or driving wheels, upon which the machine is mounted, in connection with the axle B. To the axle is attached the tongue C, to which is connected the beam D by means of adjustable links E E', Fig. 1. The links or plates E E' have a pivotal attachment with the beam D and tongue C on each side, Fig. 2, forming a jointed connection.

Secured to the axle-tree are two standards, G G, which extend up and support the shaft H in boxes at the top. To these standards are connected counter-braces a a, which extend to the tongue, to which they are fastened. On each end of the shaft H is a double-flanged

sprocket-wheel, I I'. The teeth of the wheels on one side are in the radii of the center and on the other in the form of a curved line or an inclined plane, as seen at I, Fig. 1. This form of the teeth, by means of the link belt J,

turns the sprocket-wheels in direction of the arrow b, Fig. 1, when the machine is moving in the line of the arrow c. In case the machine turns or moves back in a reverse direction of the arrow c, the link belt will then not engage the teeth of the sprocket-wheel, but slip or slide over the inclined plane of the teeth, so that it will not turn in a reverse direction

of the arrow b, but will be at rest, and not transmit motion by means of the link belt K to the sprocket-wheels L L' for operating the potato-sifting mechanism hereinafter described, as the links of the belt will slip over the inclined faces of the teeth in the sprocket-wheels so long as the movement of one or both of the driving-wheels is in reverse motion to the arrow. This mechanism is, in effect, the same in principle as the pawl and ratchet, but of different construction.

On each of the carrying-wheels A is fastened enlarged sprocket-wheels M M', to each of which is connected a link belt, J, extending to and engaging the double-flanged sprocket-wheels I I' on the shaft H, as before mentioned. From each standard G extends an arm, N, Fig. 2. Near the outer end of each arm is an elongated slot, as indicated by the dotted line d, Fig. 1. This shaft O has its bearing in these two slots, and is supported by the two arms, N N. At each end of the shaft O is keyed a tightening-pulley, P P. To the shaft O is loosely hinged or connected the bail Q. The lower end of the bail is hitched to the spring R, fastened to the tongue C. The action of the spring R, in connection with the bail Q and shaft O, causes the pulleys P P to tighten up the slack which may be made in the link belts J J which are in contact with the pulleys.

In case the link belt becomes slack by disengagement with the sprocket-wheels I, or either of them, in the turning, backing, or other movement of the machine, one or both of the pulleys P P will then be drawn down upon the link belts J J, and the slack tightened up so that the engagement of the link belts with the pulleys will take place. The slots d in the arms N N admit of the adjustment of the shaft to the slack or tension of the link belts J J.

At each end of the shaft S, Fig. 2, on which the sprocket-wheel I' is keyed, are attached cranks T T. To each crank is connected a pitman, U, respectively, by means of a slot, e, in the upper part of the pitman, as seen in Fig. 1. The slots in the pitman are somewhat shorter than the stroke of the crank. These pitmen are jointed at their lower ends, f, to the arms g of the sifter h. (Shown on one side in Fig. 1.)

The sifter consists of a series of bars or rods,

i, inserted in a head, *j*, forming an angle terminating on each side in an arm, *g*, as seen in Fig. 1.

The sifter *h* is hinged to the scraper or spear *V* at two points near the junction of the angles of the head and that of the scraper.

Fig. 3 represents one of the hinged connections referred to.

From the scraper project prongs *k*, which extend over the head of the sifter between the rods *i*, as seen in Fig. 2, which prevent weeds and dirt from clogging the jointed connection of the sifter and scraper, and aid in conveying the tubers, weeds, and dirt onto the sifter.

15 The scraper is attached to the beam by means of braces *n n*.

In operating the machine, the team is connected with the tongue in the usual way, with the driver in the rear. The scraper or shear *V*, by force of the draft, will enter the ground below the line of the potatoes, which are raised out of the ground by the scraper and passed back over the prongs onto the sifter, where they are separated from the earth by the action of the sifter induced by the crank motion in the slot of the pitman *U*. These slots *e*, as the cranks descend, admit of the sifter vibrating or moving down by its hinged connection with the scraper *V*, and as the cranks ascend in the slots *e* of the pitman the sifter is at rest during a certain period of this upward turn or stroke of the crank, until it is in contact with the upper end of the slot *e*, when the sifter is raised on its hinges quickly and suddenly. On the downward turn of the crank the sifter drops down by gravity. This movement of the sifter is intermittent and uniform, resultant from the action of the crank-connections with the slotted pitman. The sifter is at rest a sufficient time to receive its load of earth and tubers scraped up and passed over on the sifter. The crank, then acting in the slots upon the pitman, quickly raises up the

sifter with a series of lifts as the cranks revolve, thereby effectually sifting out the potatoes from the dirt.

By means of the adjustable links *E E'*, the beam may be lifted up by the lever *W*, and also the sifter with the scraper from the ground, and held in such position by a pin passing through the holes in the strap *l* under the beam, which admits of the machine being moved from place to place without the scraper and sifter being upon the ground.

What I claim for Letters Patent is—

1. In a potato-digger, the double-flanged sprocket-wheel *I*, having teeth on one side in the radial lines of its center and on the other one an incline plane, in combination with the link belt *J* and enlarged sprocket-wheel *M M'*, and driving-wheels, substantially as described, and for the purpose set forth.

2. In a potato-digger, the pitmen *U U*, provided with elongated slots at one end for the reception of the crank-pins and jointed at the lower ends to the arms *g*, and operated by means of a link belt and sprocket-wheels, in combination with the vibrating sifter hinged to the rear of the scraper and operating conjointly therewith, constructed and arranged substantially as described, and for the purpose specified.

3. In a potato-digger, the link belt *K*, in connection with the sprocket-wheels on the shafts *H S*, and cranks, in combination with the pitman jointed to the sifter, with a hinged attachment to the scraper having prongs projecting over the front portion of the scraper, and means for operating the same, as and for the purpose set forth.

In testimony whereof I affix my signature in presence of two witnesses.

JOHN BUTMAN.
